CLAIM

The ornamental design for a ring, as shown and described.

DESCRIPTION

1. Ring
- 1.1 : Perspective
- 1.2 : Front
- 1.3 : Back
- 1.4 : Right
- 1.5 : Left
- 1.6 : Top
- 1.7 : Bottom

In the representations of the design blurred lighter portions indicate disclaimed features for which protection is not being sought, whereas darker portions represent features for which protection is sought.
